UNITED STATES PATENT OFFICE

2,133,881

INKING MECHANISM FOR ROTARY INTAGLIO PRINTING MACHINES

Adolph Weiss, Brooklyn, N. Y.

Original application May 23, 1936, Serial No. 81,409. Divided and this application March 13, 1937, Serial No. 130,672

32 Claims. (Cl. 101—157)

The present invention relates to rotary intaglio printing presses having enclosed fountains within which ink is adapted to be received and applied to the printing cylinder which is partially enclosed by the fountain. This application is a division of applicant's copending application Serial No. 81,409, filed May 23, 1936, for "Adjusting and operating mechanism for enclosed ink fountains". In applicant's patents Reissue No. 18,856, granted June 6, 1933, and No. 2,014,303, granted September 10, 1935, and No. 2,055,272, granted September 22, 1936, there is shown and described an enclosed fountain of the above character.

The present invention has for an object the provision of a fountain of the above character, the construction of which is greatly simplified, and the control and maintenance of which is greatly facilitated.

A further object of the invention is to provide a construction of the above character in which the control elements are effectively protected and separated from the ink and ink vapors present within the housing.

A further object of the invention is to provide a housing in which the upper portions are so constructed and positioned that interference with the web and with access to the press is prevented.

A further object of the invention is to provide, in combination with a housing having an inking head, means for automatically draining the ink from the head prior to the removal of the head from the fountain.

A further object of the invention is to provide a housing of the above character having a construction such that the exterior surface is formed with a minimum number of projections, thus facilitating the cleaning and maintenance thereof.

A further object of the invention is to provide, in combination with an enclosed fountain having means to apply ink directly to the cylinder, mechanism by means of which the inking device may be effectively controlled while preserving a desired closure about a portion of the cylinder.

A further object of the invention is to provide an inking device in combination with structure of the above character by means of which the position of the inking device may be effectively varied by movement thereof in one or more directions in order that the device may be properly positioned with respect to printing cylinders of varying diameters.

A further object of the invention is to provide, in combination with means for moving and adjusting the position of the inking head of foun-

tains of the above character, means by which the fountain may be effectively locked in a desired position.

A further object of the invention is to provide a control mechanism for fountains having an inking head, the mechanism affording a sequential operation such that improper steps cannot be taken in assembling or dismounting the head. In this connection, it is proposed to provide a control by means of which the drain for the head is first opened by the operation of removing the head, and, after the drain has been opened, further continued operation of the control mechanism releases the felt sealing member, after which the head is unlocked.

Further objects of the invention will be apparent as it is described in connection with the accompanying drawings, wherein

Figure 1 is a view in side elevation of a housing constructed in accordance with the present invention and looking at the inking side of the housing;

Figure 2 is a plan view of the inking side of the housing shown in Figure 1 with a portion of the inking head broken away and in section to illustrate the manifolding of the inking head;

Figure 3 is a view in section, taken on line 3—3 of Figure 1, and looking in the direction of the arrows;

Figure 4 is a view in section, taken on line 4—4 of Figure 1, and looking in the direction of the arrows;

Figure 5 is a view in section, taken on line 5—5 of Figure 4, and looking in the direction of the arrows;

Figure 6 is a view in section, taken on line 6—6 of Figure 4 and looking in the direction of the arrows;

Figure 7 is a view in section, taken on line 7—7 of Figure 1 showing the elements of the housing in assembled relation;

Figure 8 is a view in section, taken on line 8—8 of Figure 3 and looking in the direction of the arrows;

With reference to the above drawings, the housing will be seen to include a sump 20 (Figure 7) having side walls 21 and 22. A pipe 23 communicates with the lowest position of the sump and permits ink to be withdrawn therefrom by a suitable pumping and recirculating mechanism 60 as shown particularly in applicant's Patent No. 2,014,303 above referred to.

Upon the side wall 21 is formed an inwardly extending horizontal flange 24, having an angularly extending flange 25. The side wall portion 55

26 is formed with a horizontal table 27 upon which one or more guide rods 28 are secured.

The guide rods 28 are mounted upon a longitudinal bracket 29 having a base portion 30 adapted to engage the plate 24 when the mechanism is in its normal operating condition, as illustrated in Figure 7. The plate 29 is formed with a plurality of pairs of spaced hinge arms 31 which cooperate with apertured bosses 32, 10 formed upon the side walls 21 and, with hinge pins 33, serve to mount the table 27 and bracket 29 hingedly in order that the structure may be swung away from its normal position to facilitate access to the fountain.

15 In order that the guide rods 28 may be properly positioned, guides 34 are formed on the bracket 29 being connected thereto by means of webs 35. The guides 34 are formed with guide ways 36 within which the guide rods 28 are slidably received, the guide rods being formed with teeth 37 which are adapted to be engaged by gears 28, mounted upon a shaft 39. The shaft 39 is journaled in bosses 40, also formed on the webs 35, thus providing a means by which all of the guide rods 28 are moved simultaneously. This motion results from an operating mechanism mounted intermediate the ends of the bracket 29 and including a housing 41 which is secured to bosses 42 and 43, formed upon the bracket 29 and base 30 plate 39, respectively. A drive shaft 44 is journaled in the housing 41 and bracket 29, being provided with a squared end 45 and a worm 46. A worm wheel 47 is splined to the shaft 39, thus transmitting power from the drive shaft 44 to the shaft 39 and gears 38. In this fashion, the guide rods 28 are moved in either direction vertically to adjust the vertical position of the wall 26.

Upon the horizontal table 27 a reentrant retaining flange 48 is provided, an inking head 49 being received upon the table. The head 49 is formed with a base 50 having an elongated groove to receive the flange 48 and be locked thereby. The base 50 is formed with spaced recesses 51 adjacent the ends thereof, such recesses serving to receive locking mechanism to be presently described. The head 49 and base 50 are secured together by means of bolts 52 and the head is locked in the position shown in Figure 4 by means of a cam 53 (Figure 6) which is mounted upon a vertical shaft 54, journaled in a boss 55 which is formed on the head 49. The shafts 54 have pinions 56 secured to the upper ends thereof, these pinions engaging a rack 57 (Figures 1, 2, 3, 4 and 7) which is slidably mounted in bosses 58 formed in the head 49 and provided with grooves 59 within which the rack 57 is slidably mounted.

The rack 57 is also shown in Figure 7 wherein the mechanism by means of which the locking cams 53 are operated is illustrated in greater detail. For this purpose, a shaft 60 is mounted in the head 49 and provided with a manually operable crank 61 as well as a pinion 62 which engages the teeth of the rack 57. By turning the crank 61, the rack 57 may be moved in either direction, causing the shafts 54 and cams 53 to be turned. Upon opposite sides of each of the shafts 54, and lying substantially in planes passing through the axes of shafts 54 and perpendicular to the wall 26 are stub shafts 63 and 64 secured in the platform 27. Stub shaft 63 is provided with a roller 65 while shaft 64 is provided with a roller 66 having a flanged portion 67. Each of the cams 53 is formed with a tapered

surface 68 which is adapted to be engaged under the flanged portion 67 to lock the head in the position shown in Figure 4. When the rack is moved in either direction from the position shown in Figure 4, the cams 53 are turned and, upon 5 motion thereof through 180 degrees, the rollers 65 are engaged and the base 50 is retracted from the flange 48 to unlock the head and permit the same to be removed.

In order that the fountain may be effectively 10 sealed to prevent substantial evaporation of the volatile ingredients of ink that may be used in the housing, the head 49 is provided with a removable bracket 69 which is locked in a normal sealing position by means of a spring lock plate 15 70. To this end, the bracket is formed with a plate 71 having a positioning flange 72. The head 49 is formed with a longitudinal shoulder 73 against which the flange 72 abuts to position the bracket 69 properly with respect to the head. 20 Within the bracket 69 is provided a sealing strip 74 of any suitable material such as felt, or the like, this strip being secured to the bracket 69 by means of screws 75 of the like. A positioning strip 76 is also provided within the bracket 69, 25 screws 77 securing the same in position in order that the positioning strip 76 may maintain the sealing strip 74 effectively in the sealing position shown in Figure 4. The positioning strip 76 is formed with a cutaway portion 78 along the portion 30 thereof adjacent an ink discharge nozzle 79 (Figures 3 and 7) to be described in greater detail hereinafter. The end of the head 49 adjacent the cylinder is formed with a boss 80 against which the bracket 69 urges the sealing 35 strip 74 and positioning strips 74 and 76 when the locking strip 70 has been moved to a locking position.

It will thus be seen that the bracket 69 may be readily removed from the head 49 when the spring lock strip 70 is moved into a retracted position. In the normal position of the spring strip 70, however, as illustrated in Figures 3 and 4, the bracket is maintained in a normal sealing position. The mechanism for actuating the locking strip 70 comprises eccentrics 81 secured to 40 the shafts 54. Links 82 are formed with apertures 83 which receive the eccentrics 81 and thus transmit reciprocating motion from the rotating shafts 54 to the links 82. At the other ends of links 82, apertured bosses 84 are provided, these 45 bosses receiving stub shafts 85 which extend through a sealing plate 86 carried by the head 49, this plate being formed with apertures 87 to receive the shafts 85. Above the sealing plate 86, the shafts 85 are provided with guides 88 which are received in grooves 89, formed within the head 49. Guides 88 are so mounted with respect to apertures 87 that the apertures 87 are closed when the lock plate 70 is in clamping position. The head 49 is also formed with slots 90 50 in which the shafts 85 are slidably received, bushings 91 being provided therein for this purpose. A reinforcing strip 92 is provided beneath the spring locking strip 70, nuts 93 securing the foregoing elements in the assembled position 55 shown in Figure 4.

It will thus be seen that, when the eccentric locks 53 are disengaged, the lock strip 70 will be retracted to permit the bracket 69 to be removed. The foregoing operations occur simultaneously 70 inasmuch as the mechanism by means of which each operation is accomplished is actuated by the common manually operated crank 61.

Intermediate the ends of the head 49 ink channels and ducts are provided to supply ink to 75

the nozzle 79. Within the head 49 is secured a manifold member 94. The head 49 is secured, as illustrated in Figure 7, to the bottom plate 50 by the bolts 52 and the manifold member 94 is secured to the upper portion of the head 49 by means of bolts 95. The sealing plate 86 extends longitudinally of the head and lies between the manifold member 94 and the upper portion of the head to serve as a means to seal the manifold member from the adjacent portions of the head to which the said member is secured. Bolts 96 additionally secure the manifold member to the head and, by extending through the member, also secure elbow connections 97 to the manifold member. Flanges 98 are formed on the elbow connections 97 and are secured to the outer wall 99 of the head 49 by means of bolts 100. As illustrated in Figure 2, the manifold member is formed in a plurality of sections as indicated by the division lines 101. Each section is formed with an outer lip 102 which coacts with the adjacent portion of the head to form the nozzle 79. In order that a uniform amount of ink may be supplied to the nozzle over the entire length thereof, the manifold member is formed with passages 103 which communicate with ducts 104. Ducts 104 in turn communicate with ducts 105 which, in turn, communicate with ducts 106. Ducts 106 communicate with ducts 107 which in turn communicate with the nozzle 79, thus affording an even distribution of ink to the portion of the nozzles supplied by such ducts. Obviously, the cross-sectional area of these ducts diminishes as the ducts progress to the various stages of division of the ink flow. The passages 103 are supplied with ink from a manifold 108, formed in the elbow 97 (Figure 2). Each of the elbows 97 is formed with a flange 98 which is elongated and formed with a similar elbow, as shown in Figure 2. A longitudinal duct 109 is formed in the flange 98, this duct communicating through a passage 110 with a manifold passage 111, formed in the side wall 99 of the head 49 (Figures 2 and 7). A pipe connection 112 with the manifold passage 111 permits ink to be delivered to the said passage from a suitable circulating mechanism, not shown.

Within the side wall 99, and serving as a wall of the manifold passage 111, is a plate 113 upon which the flanges 98 are mounted. The passages 110 are formed in plate 113 to afford communication between the passages 109 and 111 and the plate 113 is formed with a horizontal flange 114 (Figure 7) within which the lower end of shaft 60 is journaled. In order that ink may be bypassed around the nozzle 79, a conduit 115 is provided between the manifold passage 111 and the interior of the ink housing. A valve chamber 116 is formed in this passage and adapted to receive a valve plug 117 (Figure 7). A shaft 118 is secured to the valve 117 and journaled in the flange 114, the upper end thereof being provided with a pinion 119 which engages a gear 120, secured to the shaft 60. In this fashion, when the manually operated crank 61 is actuated to release the head 49 from its sealing position and release the sealing bracket 69 from like position, the valve 117 is opened to by-pass ink from the manifold passage 111 to the ink housing.

Upon the side of the housing opposite from the inking head 49, a doctor supporting mechanism is provided, this mechanism being described specifically in the parent application Serial No. 75 81,409 of which this application is a division. A

detailed description of these elements is, therefore, unnecessary herein.

It will thus be seen that the construction described herein provides an improved fountain wherein the operating parts are enclosed and maintained away from the ink and ink vapors within the housing, the construction also being such as to facilitate the cleaning and maintenance thereof, particularly in view of the minimum number of projections from the fountain housing. All locking members are convenient and accessible and the control mechanism is such as to insure a proper sequence of operations to prevent damage to the mechanism.

Moreover, inasmuch as the inking head as well as the doctor mechanism is positioned more to the side of the cylinder than above the same, ready accessibility to the press and web is afforded. Inasmuch as the ink does not drain from the head by gravity, the inner lock with the control member insures opening of the drain prior to removal of the head.

While the invention has been described with specific reference to the construction shown in the accompanying drawings, it is not to be limited, save as defined in the appended claims.

I claim:

1. Inking mechanism for a rotary intaglio printing machine comprising a side wall having a platform member, an inking head member removably seated on the platform, locking means comprising cooperative longitudinal locking means formed on the said platform and head, a stud on one of the members, a cam on the other of the members, and means to actuate the cam to lock the members in assembled position.

2. Inking mechanism for a rotary intaglio printing machine comprising a side wall having a platform member, an inking head member removably seated on the platform, locking means comprising cooperative longitudinal locking means formed on the said platform and head, a pair of studs on one of the members, a pair of rotatable cams on the other of the members adapted to engage the studs, and means to rotate the cams to lock the members in assembled position.

3. Inking mechanism for a rotary intaglio printing machine comprising a side wall having a platform member, an inking head member removably seated on the platform, locking means comprising cooperative longitudinal locking means formed on the said platform and head, a pair of studs on one of the members, a pair of rotatable cams on the other of the members adapted to engage the studs, and means to rotate the cams simultaneously to thereby exert a simultaneous locking action on the locking means.

4. Inking mechanism for a rotary intaglio printing machine comprising a side wall having a platform member, an inking head member removably seated on the platform, locking means comprising cooperative longitudinal locking means formed on the said platform and head, two pairs of spaced roller studs on one of the members, a pair of rotatable cams on the other of the members to selectively engage the studs of the respective pairs, and means to rotate the cams into selective engagement with the respective studs, the studs being so positioned that actuation of certain ones thereof by the cams causes the locking means to be engaged while actuation of other of the studs causes the locking means to be released.

5. Inking mechanism for a rotary intaglio printing machine comprising a side wall having a platform member, an inking head member removably seated on the platform, locking means comprising cooperative longitudinal locking means formed on the said platform and head, two pairs of spaced roller studs on one of the members, a pair of rotatable cams on the other of the members to selectively engage the studs of the respective pairs, and means to rotate the cams simultaneously into selective engagement with the respective studs, the studs being so positioned that actuation of certain ones thereof by the cams causes the locking means to be engaged while actuation of other of the studs causes the locking means to be released.
6. Inking mechanism for a rotary intaglio printing machine comprising a side wall having a platform member, an inking head member removably seated on the platform, locking means comprising cooperative longitudinal locking means formed on the said platform and head, roller studs on one of the members, a pair of rotatable cams on the other member adapted to engage the studs, pinion gears mounted on the cams, a slide having rack teeth formed thereon and meshing with said gears, and means to move the slide to rotate the cams simultaneously in either direction.
7. An inking head adapted for use with an enclosed ink housing for a rotary intaglio printing machine and having a sealing strip, a holder for the strip removably mounted on the head, locking means for securing the holder to the head, and means within the head to actuate the locking means.
8. An inking head adapted for use with an enclosed ink housing for a rotary intaglio printing machine and having a sealing strip, a holder for the strip removably mounted on the head, locking means comprising a cover plate adapted to cooperate with the holder, and means to actuate the cover plate.
9. An inking head adapted for use with an enclosed ink housing for a rotary intaglio printing machine and having a sealing strip, a holder for the strip removably mounted on the head, locking means for securing the holder to the head, said locking means including actuating means partly outside and partly within the head, and means cooperating with the last named means to maintain the head in substantially sealed condition.
10. In combination with an enclosed ink housing for a rotary intaglio printing machine, a side wall having a platform thereon, an inking head removably seated thereon, a sealing strip having a holder removably mounted on the head, locking means to secure the head to the platform, locking means to secure the strip and holder to the head, and common means to actuate the two said locking means.
11. In combination with an enclosed ink housing for a rotary intaglio printing machine, a side wall having a platform thereon, an inking head removably seated thereon, a sealing strip having a holder removably mounted on the head, locking means to secure the head to the platform, locking means to secure the strip and holder to the head, and common means within the head to actuate the two said locking means.
12. In combination with an enclosed ink housing for a rotary intaglio printing machine, a side wall having a platform thereon, an inking head removably seated thereon, a sealing strip having a holder removably mounted on the head, locking means to secure the head to the platform, locking means to secure the strip and holder to the head, and common means to actuate the two said locking means.
13. In combination with an enclosed ink housing for a rotary intaglio printing machine, a side wall having a platform thereon, an inking head removably seated thereon, a sealing strip having a holder removably mounted on the head, locking means to secure the head to the platform, locking means to secure the strip and holder to the head, and common means to actuate the two said locking means, the common actuating means functioning to release the strip and holder prior to releasing the head from the platform.
14. In combination with an enclosed ink housing for a rotary intaglio printing machine, a side wall having a platform thereon, an inking head removably seated thereon, a sealing strip having a holder removably mounted on the head, locking means to secure the head to the platform, locking means to secure the strip and holder to the head, and common means to actuate the two said locking means, the common actuating means functioning to release the strip and holder prior to releasing the head from the platform and to engage the head on the platform prior to locking the strip and holder upon the head.
15. Inking mechanism for a rotary intaglio printing machine comprising an inking head having an intake port, means forming a dividing manifold passage in a wall of the head, a plurality of distributing manifolds having dividing manifold passages communicating with the first passage, providing successive stages of distribution, and a discharge nozzle on the head communicating with the last named passages.
16. Inking mechanism for a rotary intaglio printing machine comprising an inking head having an intake port, means forming a dividing manifold passage in a wall of the head, a plurality of distributing manifolds having dividing manifold passages communicating with the first passage, providing successive stages of distribution, all of said manifolds being mounted on the interior of the head, and a discharge nozzle on the head communicating with the last named passages.
17. Inking mechanism for a rotary intaglio printing machine comprising an inking head, means thereon to discharge ink therefrom, and means in the head formed with ducts communicating with the discharge means and forming a divisional ink distributing system and a drain valve communicating with the lowermost level of the system.
18. Inking mechanism for a rotary intaglio printing machine comprising a removable inking head, locking means for securing the head in a normal operative position, a drain valve for the head, and common means to actuate the locking means and the drain valve.
19. Inking mechanism for a rotary intaglio printing machine comprising a removable inking head, locking means for securing the head in a normal operative position, a drain valve for the head, and common means to actuate the locking means and the drain valve, the last named valve being adapted to close the drain valve prior to locking the head, and open the valve prior to unlocking the head.
20. Inking mechanism for a rotary intaglio printing machine comprising a removable inking head, locking means for securing the head in a normal operative position, a drain valve for the head, and common means to actuate the locking means and the drain valve.

- printing machine comprising a removable inking head, locking means for securing the head in a normal operative position, a sealing strip removably carried by the head, means to secure the strip on the head, a drain valve for the head, and common means for operating the drain valve, the locking means, and the strip securing means. 5
21. Inking mechanism for a rotary intaglio printing machine comprising a removable inking head, locking means for securing the head in a normal operative position, a sealing strip removably carried by the head, means to secure the strip on the head, a drain valve for the head, and a manually operable means for operating the drain valve, the locking means and the strip securing means in a predetermined sequence. 10
22. Inking mechanism for a rotary intaglio printing machine having a sealed ink housing chamber comprising a removable inking head, means to mount the head to form a portion of the housing of the chamber, and means for locking the head in a normal operative position, said locking means being sealed from the interior of the housing. 15
23. Inking mechanism for a rotary intaglio printing machine having a sealed ink housing chamber comprising an inking head, means to mount the head to form a portion of the housing of the chamber, a drain valve for the head, and operating means for the valve, said valve and operating means being sealed from the interior of the housing. 20
24. Inking mechanism for a rotary intaglio printing machine comprising an inking head having walls forming a box-like sealed enclosure, and means forming a sealed ink distributing system within the enclosure and forming a portion of the enclosure said means directing ink through the head. 25
25. Inking mechanism for a rotary intaglio printing machine comprising a removable inking head having walls forming a box-like sealed enclosure, means to lock the head in a normal operative position, and means within the enclosure to operate the locking means. 30
26. Inking mechanism for a rotary intaglio printing machine comprising an inking head having walls forming a box-like sealed enclosure, and means forming a sealed ink distributing system within the enclosure and directing ink through the head, a drain valve the intake port of which communicates with the lowermost level of the system, the discharge port of the valve communicating with the exterior of the head, and actuating means for the valve, said valve and actuating means being mounted within the sealed enclosure and the actuating means being sealed from the system. 35
27. Inking mechanism for a rotary intaglio printing machine comprising a removable inking head having walls forming a box-like sealed enclosure, means to lock the head in a normal op- 40
- erative position, a sealing strip removably carried by the head, means to secure the strip in a normal position, a drain valve for the head, and means within the head to operate the locking means, the securing means and the valve. 5
28. Inking mechanism for a rotary intaglio printing machine comprising a removable inking head having walls forming a box-like sealed enclosure, means to lock the head in a normal operative position, a sealing strip removably carried by the head, means to secure the strip in a normal position, a drain valve for the head, means within the head to operate the locking means, the securing means and the valve, and means exteriorly of the head to actuate the operating means. 10
29. Inking mechanism for a rotary intaglio printing machine comprising an inking head having walls forming a box-like sealed enclosure, and means forming a sealed ink distributing system within the enclosure and forming a portion of the enclosure and directing ink through the head, the head having an intake port and a discharge nozzle to discharge ink from the head. 15
30. Inking mechanism for a rotary intaglio printing machine adapted to accommodate printing cylinders of varying diameters and having an enclosed ink housing chamber comprising an inking head for inking the cylinder, a side wall, an adjustable wall plate movably mounted on the side wall supporting the inking head and movable therewith to position the head relative to cylinders of varying diameters and maintain a sealing relation between the head and the walls, means for adjusting the position of the head, and means for maintaining the last-named 20 means out of contact with the interior of the enclosed ink housing chamber. 25
31. Inking mechanism for a rotary intaglio printing machine adapted to accommodate printing cylinders of varying diameters and having an enclosed ink housing chamber comprising an inking means, means to mount the last named means adjustably to accommodate printing cylinders of varying diameters, means to adjust the position of the inking means, and means for 35 maintaining the last-named means out of contact with the interior of the enclosed ink housing chamber. 40
32. Inking mechanism for a rotary intaglio printing machine adapted to accommodate printing cylinders of varying diameters and having an enclosed ink housing chamber comprising an inking means, means to mount the last named means removably and adjustably to accommodate printing cylinders of varying diameters, means exteriorly of the chamber to lock the inking means in an adjusted position, means to adjust the position of the inking means, and means for maintaining the last-named means out of contact with the interior of the enclosed ink housing chamber. 55

ADOLPH WEISS.
